UNITED STATES PATENT OFFICE.

ALVA L. SCOVILLE, OF LOS ANGELES, CALIFORNIA.

RECORDING AND CLASSIFYING SYSTEM.

Application filed April 13, 1921, Serial No. 461,053. Renewed June 30, 1925.

To all whom it may concern:

Be it known that I, ALVA L. SCOVILLE, a citizen of the United States, residing at Los Angeles, in the county of Los Angeles and 5 State of California, have invented new and useful Improvements in Recording and Classifying Systems, of which the following is a specification.

This invention relates to a system of recording and classifying random facts, notes, data and the like.

Students, scientists, professional and business men, and in fact nearly all people who strive for intellectual improvement, have 15 long felt the necessity for a simplified and inexpensive system whereby facts, data and various bits of information collected at random can be recorded and easily classified and reclassified regardless of volume, and made 20 available for instant and ready reference. Prior systems are too limited in expansion and too costly and cumbersome in application.

The present invention is based upon a 25 principle of nature found in the growth and expansion of the brain due to multiplication of the cells thereof. Each cell contains within it a nucleus or seed capable of reproducing a second cell so that when one cell 30 becomes filled or expanded to capacity it sub-divides and forms a second cell. The present system following the same principle employs a cell as its smallest unit. Each cell is of fixed and uniform capacity and 35 contains one or more main classes, and each main class, if desired, is divided into one or more sub-classes. The main classes are indexed by means of a novel and inexpensive follower block which is automatically expandable and also is arranged to exhibit 40 plainly the title of the main class. The sub-classes are divided and separated by means of division cards having tops showing the title of the sub-class. Within each sub- 45 class are any desired number of sheets or cards upon which data or information is written for preservation and classification. By means of the expandable follower block the individual data-bearing cards are held 50 closely in place whether a few or many are present. When the capacity of the cell is reached a second cell is started in a similar manner, sub-dividing or reclassifying according to what the classification demands. 55 A number of cells go to fill a box or till. Each box or till is fitted with a cover, and

any number of these may be filed away in tiers or side by side on shelves.

In the accompanying drawings,

Fig. 1 shows a perspective view of a cell 60 fitted with individual data-bearing cards, division cards separating the data bearing cards into sub-classes, and an expandible follower block at the rear bearing on its top the name of the main class. 65

Fig. 2 shows a perspective view of one of the boxes or holders for removably receiving a number of these individual cells.

Fig. 3 shows a perspective view of a 70 larger form of box or holder.

Fig. 4 shows a plan view of a still larger holder to removably receive a quantity of these individual cells.

Fig. 5 shows a sectional view taken through one of the individual cells illustrating the follower block in expanded position. 75

Fig. 6 shows a similar view illustrating the follower block in contracted position.

Fig. 7 shows a number of boxes or holders 80 of the type illustrated in Figs. 2 and 3 filed away in vertical position side by side, like books.

Fig. 8 shows a number of holders of the type shown in Fig. 4 filed away in tier 85 fashion.

I show in Fig. 1 a suitable form of cell which is a rectangular structure 10 either with or without a bottom. Each cell receives one or more follower blocks 11 shaped as shown in cross section in Fig. 5. This 90 follower block 11 is made of cardboard with inclined legs and a flat ridge 12 at the top to receive written or printed data showing the title of the main class. The natural tendency of the legs is to spread apart and keep the individual cards in compacted form within the cell whether there be few or many of these cards. The individual data-bearing cards are indicated at 13, and these may, if desired, be further sub-divided by division cards 14 having tabs 15 to contain the name of the sub-class. When the main class expands to the capacity of the cell by reason of the addition of data-bearing cards a second cell is started with the more active sub-class as a nucleus. A follower block is placed in the new cell with the title of the sub-class thereon so that the latter now assumes the form and nature of the new main class. A number of these cells, say four, as shown in Fig. 2, or ten, as shown in Fig. 3, 105 are detachably and removably fitted in a

box-like structure 16, 16' which when filled may be labeled and filed away on a shelf after the manner of a book. In case a larger volume of cells is required a till 17 5 like that shown in Fig. 4, containing say sixty individual and removable cells may be used. This till as well as the boxes shown in Figs. 2 and 3, has a cover 18 and a number of these tills can be filed away tier upon tier.

A small-sized card is preferably used in this system and it is intended that each card shall contain but one fact or thought. Generally speaking, the brain itself is capable 15 of receiving and retaining but one impression at a time, and hence as a system of learning the present arrangement is ideal. Following as it does the development of cells of the brain, a system of this nature if 20 properly kept should graphically and accurately represent the development and growth of the brain over any given period of time. It teaches the user to classify and reclassify random facts so that the cells of 25 the brain and the cells of the recording and classifying system are reciprocally expanded and improved. By reason of the expandable follower block a cell can be made to hold one sheet or a great many, and when 30 the cell is full, just as in nature, it is capable of sub-division and the contents of the cell such as the heads and sub-heads into which 35 the second cell is divided should be arranged for new growth and orderly expansion. The cells being arranged in boxes or trays with telescopic covers are kept free of dust 40 and dirt and may be filed away on shelves or otherwise where they may be kept indefinitely without danger of becoming destroyed or injured.

The present system is several times cheaper to maintain than any prior known system. The individual sheets are preferably of small size and of thin paper, and 45 may be used with the same freedom as

ordinary note paper. In practice the user of this system will carry a number of these slips with him at all times upon which to make notes, and subsequently these slips can be filed away in their proper place 50 where they will be instantly available for future reference.

The individual cells or trays it will be noted, expand into holders or tills and the latter are suitable for permanent filing, 55 being each provided with a cover. These may be filed side by side as shown in Fig. 7, or tier upon tier as shown in Fig. 8. Thereby the present system is adaptable to any requirement and is capable of indefinite 60 expansion.

Having thus described my invention what I claim and desire to secure by Letters Patent is:—

1. An apparatus for recording and keeping data comprising a box-like receptacle with a removable cover, a plurality of small box-like cells removably fitted in said receptacle, memoranda cards fitted loosely in said cells and an expandible follower in each cell 70 in the form of an inverted V made of comparatively stiff paper whereby the legs tend to spread apart to compact the memoranda cards, said follower being formed at its top with a flat index portion integral with the 75 legs.

2. In a recording and classifying system a tray, data-bearing cards removably received in the tray, a follower for maintaining the cards in proper position, said follower being formed of a single card board in the shape of an inverted V, the legs of 80 which tend normally to spread apart whereby to compact the cards, said follower having a flat ridge at its top formed integral with the legs to receive a general designation explanatory of the subject matter contained on the cards.

ALVA L. SCOVILLE.
